Earl C. Applegate, Chicago, Ill.

Application March 19, 1954, Serial No. 417,420

10 Claims. (Cl. 51—187)

The present invention relates to an implement commonly known as a hand sander, wherein a strip of coated abrasive material, such as sandpaper and the like, is securely held on a holder of such size and shape that it may be readily grasped by the user and manually operated in a variety of surface finishing operations.

The objects of this invention are to provide an improved implement of the character indicated which will be particularly simple in construction and economical to manufacture, and which will be durable and efficient in use.

It is also an important object of this invention to provide clamping means for securely holding the strip of abrasive material against unintentional removal from the holder and which at the same time affords facilities for quickly and easily replacing a used strip with a fresh one.

Other and further features and objects of the invention will be more apparent to those skilled in the art upon a consideration of the accompanying drawings and following specifications, wherein is disclosed certain exemplary embodiments of the invention, with the understanding, however, that such changes may be made therein as fall within the scope of the appended claims, without departing from the spirit of the invention.

In the drawings:

Fig. 1 is a top plan view, with parts in section, of an implement for sanding operations constructed in accordance with a preferred embodiment of this invention.

Fig. 2 is a sectional view taken along line 2—2 of Fig. 1.

Fig. 3 is a top perspective view of the clamping means as shown in Fig. 1.

Fig. 4 is a fragmentary sectional view showing a modified form of clamping means.

With more particular reference to the drawing, the specific embodiment of the invention as shown in Figs. 1, 2 and 3 includes a holder in the form of an elongated block of wood or the like having front and back walls 10 and 11, respectively, opposed longitudinal side walls 12 and 13 which cooperate to define top and bottom sides 14 and 15, respectively, of generally rectangular plan.

A socket formed in the top wall 14 intermediate of and spaced from the front and back walls 10 and 11, and intersecting the side walls 12 and 13, presents a bottom face 16 which terminates fore and aft in an undercut area or groove 18 and an opposite undercut area defined by a rearwardly offset back wall 19 and an overhanging lip 19a. A plate 20, of metal or other suitable material, insertable in the socket is provided with an edge 21 which is normally urged toward a position of engagement in the groove 18 under stress of an expansible pad 22 of rubber or the like interposed between an upstanding flange 23 on the plate 20 parallel to the edge 21 and the surface of the back wall 19. The pad 22 is preferably of such dimension as to fill the space between lip 19a and the surface of the bottom wall 16 opposite thereto and is suitably secured by adhesive or the like to the back wall 19.

2

Reference numeral 24 designates a strip of coated abrasive, such as sandpaper or the like, which preferably conforms in width to the dimension of the block measured between the side walls 10 and 12. The strip 24 is also of such length as to be wrapped about the bottom side 15 and to provide an end portion 25 reaching rearwardly across the surface of the top wall and into the socket, and an end portion 26 reaching in the opposite direction for entry in a slot 27 formed at the rounded juncture of the back wall 11 and the surface of the top wall 14 extending forwardly therefrom. The end portion 25 reaching into the socket and across the groove 18 so as to underlie the edge 21 of the plate 20, is accordingly locked against withdrawal from the groove 18 under pressure applied by the rubber pad 22 acting against the flange 23 of the plate 20.

The wall of the socket containing the groove 18 is preferably inclined forwardly and outwardly from the bottom 16. Thus during insertion of the plate 20 toward 20 a position to clamp the underlying end 25 of the abrasive strip 24 while the flange 23 is in abutment with the rubber pad 22 such inclined surface of the socket wall cooperates with the edge 21 of the plate to compress the pad 22 as the plate is pressed toward the bottom 16. 25 The frictional engagement developed between the edge 21 of the plate and the end 25 of the strip 24 while the plate is depressed into a seated locking position in the socket also aids in tensioning the strip into a taut state.

To further facilitate handling of the plate 20 while 30 being moved toward and away from a clamping position in the socket the plate 20 is folded or bent upon itself as at 28 to form a finger engaging tab extending parallel to the edge 21.

The surface of the top side of the block between the 35 socket and the front wall 10 is covered with a layer 30 of suitable relatively soft, highly resilient material, such as for example, as sponge rubber. Not only does this layer 30 provide a yieldable cushion for the abrasive strip positioned over the area occupied by said layer for the purpose of providing greater accessibility to work surfaces of irregular contour but to act as an expansion member 40 to increase tension on the abrasive strip when the layer 30 is compressed.

The bottom wall includes a forward area 31 which 45 is inclined forwardly and upwardly in relation to the rearward portion of said bottom wall. The latter portion is preferably covered with a layer of cork 32 or similar material, against which the abrasive strip 24 has support across said portion.

Fig. 4 illustrates a socket and clamping plate of somewhat modified construction wherein the back wall of the socket presents a flat face 33 inclined forwardly from the junction with the bottom 16 throughout the depth of the socket so as to present a rigid abutment for engagement with the flange 23 of the plate. Stress on the plate to normally urge its edge 21 into interlocked engagement with the groove 18 is obtained through action of the arched area 34 which functions as a finger tab and also exerts pressure in directions of the groove and 55 the back wall of the socket by virtue of resistance to contraction of such arched area.

It will be appreciated from the foregoing that the clamping arrangement thus provided by the present invention makes it convenient to use either the top or bottom sides of the holder as a work engaging face and that while so keeping both top and bottom sides readily applicable to such work the clamping arrangement assures the maintenance of an abrasive strip in firmly and tautly bound engagement with the holder. Furthermore, the clamping arrangement of this invention provides for easy removal of the abrasive strip and for easy replacement of a fresh strip.

What is claimed is:

1. In a hand implement for performing abrading operations, a generally rectangular block-like base having opposed top and bottom walls, a socket opening through one of said walls presenting a bottom face in undercut relation to the opposed wall surfaces of the socket rising from said bottom face, a strip of abrasive coated material wrapped about one of the aforesaid walls of the base remote from the wall containing said socket, means for anchoring one end of said strip away from said socket, and means cooperating with said socket for locking said other end of the strip in said socket including a plate presenting an edge portion engageable with the junction of one of said opposed wall surfaces of the socket and said bottom face of the socket, and resilient means engaging said plate along a second edge portion parallel to said first named edge portion and the other of said opposed wall surfaces of the socket to urge said first named edge portion of the plate toward said junction.

2. In a hand implement as defined in claim 1 wherein said resilient means comprises a compressible pad having abutment with the wall surface of the socket opposite the wall surface which faces the first named edge portion of the plate.

3. In a hand implement as defined in claim 1 wherein the plate is provided with a flange at the edge thereof opposed to the first named edge of the plate, and said resilient means comprises a compressible pad interposed between said flange and the wall surface of the socket opposite thereto.

4. In a hand implement as defined in claim 1 wherein said socket extends the full dimension of the block measured between the longitudinal edges of the wall containing said socket.

5. In a hand implement as defined in claim 1 wherein said plate is provided with a finger tab.

6. In a hand implement as defined in claim 1 wherein said plate is folded upon itself along a line parallel to said edge portions of the plate.

7. In a hand implement as defined in claim 1 wherein said resilient means includes an area of the plate folded upon itself along a line parallel to said edge portions of the plate.

8. In a hand implement as defined in claim 1 wherein the wall surface of the socket facing said first named edge portion of the plate is inclined toward the opposite wall surface of the socket in the direction of the bottom face of said socket.

9. In a hand implement as defined in claim 1 wherein the wall of the base opposite the wall containing the socket presents a flat area in a plane inclined toward said wall containing the socket.

10. In a hand implement as defined in claim 1 wherein the wall of the base containing the socket is provided with a facing of rubber throughout an area extending from one end of the base to position adjacent said socket.
